UNITED STATES PATENT OFFICE.

FRITZ GENTZCKE, OF ZEESEN, NEAR KONIGS WUSTERHAUSEN, GERMANY, ASSIGNEE,
BY MESNE ASSIGNMENTS, TO AMERICAN INVESTIGATION CORPORATION, OF NEW
YORK, N. Y., A CORPORATION OF MARYLAND.

SLEEPING COMPARTMENT.

Application filed July 2, 1923. Serial No. 649,070.

To all whom it may concern:

Be it known that I, FRITZ GENTZCKE, citizen of the German Republic, residing at Zeesen, near Konigs Wusterhausen, Germany, have invented certain new and useful Improvements in Sleeping Compartments (for which I have filed an application for patent in Germany August 26, 1922), of which the following is a specification.

10 My invention relates to improvements in sleeping-compartments for ships, railway cars, dirigible balloons, and other aircraft (and all vehicles for use in the transportation of passengers).

15 In order to save weight and space the beds in the cabins of airships are usually disposed or arranged in pairs, similar to the arrangement in the railroad sleeping cars, one above the other one in a manner 20 that the lower bed of each pair may be utilized as a seat in the day-time, while the upper one can be let down like the leaf of a table in order to afford a back to the seat which thus has the shape of a sofa. In 25 the day-time a narrow passage only is required along the sofa or between the two sofas, eventually for placing a table therein, a wider main passage being provided in front of the cabins in the manner of a corridor connecting the entrances of the several 30 cabins.

It is desirable for each passenger to have a room of his own for the night and for 35 dressing and undressing purposes which can be closed so as to prevent other passengers from entering or looking into the same. The idea is to provide spaces or rooms of the kind without enlarging the space or passage required in the day-time and without 40 dividing the latter by stationary partitions so that separated rooms, one for each passenger, will be available for the night-time only.

The object of the present invention is to 45 solve the above problem. To this end curtains or readily displaceable partitions are employed for dividing the passage along the beds and enclosing part of the hereinbefore mentioned main passage in a manner 50 that the space above and over each single bed will be in open communication with one of the adjacent divisions or sections established in the said passages and limited or enclosed by the said curtains or displaceable

partitions to form a closed compartment. In 55 this way a separate dressing room will be provided for each passenger, in open communication or connection with his bed or bedroom and duly protected against insight.

In the accompanying drawings which 60 diagrammatically illustrate by way of example a few embodiments of the invention only,

Fig. 1 is a horizontal view of the upper 65 story of a cabin of an airship or car for use as a sleeping room,

Fig. 2 is a similar section of the lower story,

Fig. 3 is a vertical section on the line 70 A—B of Fig. 1;

Fig. 4 is a vertical section on the line 75 C—D of Fig. 1 and

Fig. 5 is a vertical section on the line 80 E—F of Figure 1.

Fig. 6 is a horizontal view of a cabin 85 showing the arrangement in case of a single pair of superposed beds only.

Fig. 7 is a plan view showing an arrangement whereby the two upper beds may be accessible from the main passage while the 90 lower beds are accessible from the lateral passage 6 therebetween.

In Figures 1 to 5 the beds and the dressing rooms belonging together are designated with like numerals, such as 1—1, 2—2, etc., 95 and the communication is indicated by arrows.

In the embodiment illustrated in Figures 1 to 6 the cabin of the car comprises two pairs of superposed beds and a passage 90 therebetween. In the day-time the two upper beds 1¹ and 2¹ are turned down about hinges (not shown) into a vertical position to form, in connection with the two lower beds 3¹ and 4¹, Figure 6, two seats or sofas 7 95 and 8 with the passage 6 therebetween. The main passage or corridor 5 is, in the day-time, in open communication with the several cabins provided alongside. The said main passage 5 extends either midway between two rows of oppositely located cabins or at the one side of the car with the cabins in one row only on the other side thereof. For the night first the passage 6, Figure 6, is shut off towards the two spaces 3 and 4 100 above the lower beds 3¹ and 4¹ by means of curtains 9, Figures 3 and 4, which are suitably connected with the upper beds 1¹ and 2¹.

and preferably also with the lower beds 3¹ and 4¹, to allow of displacement or removal.

The spaces 3 and 4 constitute two dressing rooms and belong to the lower beds 3¹ and 4¹, Figure 3. The said rooms 3 and 4, situated in front of the outer or fore ends of the beds, occupy each a portion of the main passage 5, as will be clearly understood from an inspection of Figures 1 and 2. The passage 6 intermediate is divided into two rooms 1 and 2, the room 2 being in communication with the upper bed 2¹, while the room 1 is in communication with the upper bed 1¹, as will be clearly seen in Figures 1 to 4. In Figure 1 a curtain 14 of U-shaped cross-section, when displayed, shuts off or encloses the dressing room in the passage 6. The space above the bed 2¹ and in communication therewith is shut at its front end through a curtain 15 and half of its length is shut by means of a curtain 17. The space above the bed 1¹ is closed at its front end through a curtain 16 and half of its length is shut by curtain 18. The dressing room 1 is accessible from the main passage 5 through (part of) the room 2 on shifting the curtain 14 aside, whereby the size of the room 2 is temporarily decreased to allow the owner of room 1 to step in between the beds and the curtain.

If desired, however, the arrangement may be carried out in a manner that the two upper beds 1¹ and 2¹ will be accessible from the main passage 5, whilst the two lower beds 3¹, 4¹ are accessible from the cabin passage 6. In the embodiment of the invention shown in Figure 7 the inner passage is subdivided by a partition such as a curtain or the like, to afford two dressing rooms, which will be accessible from the passage 6.

All of the curtains employed for shutting and enclosing the single bed-rooms may be provided with readily applicable devices for locking the same. Within each bed-room the necessary fittings and containers for the accommodation of toilet-articles and clothes may be provided. For the illumination of the rooms from outside translucent portions may be inserted in the curtains or partitions and lamps may be located preferably in the main passage 5.

What I claim is:—

1. Sleeping quarters in the car of an aerial vessel comprising tiers of beds at one side

of a main passage and on either side of a lateral passage in communication with the main passage, the beds being arranged parallel with the lateral passage, means for providing separate dressing rooms for each of the beds comprising for the lower beds a chamber-like partitioning means arranged at the ends of each of the beds adjacent the main passage and closing off a space in front of said ends, and for the upper beds a chamber-like partitioning means in the lateral passage plus a curtain depending from the upper bed the balance of the length of the same not included by the said partitioning means, and a curtain depending from the other upper bed the full length of the same, passage to one of the dressing rooms for the upper bed being had between said bed length curtain and chamber-like compartment for the other upper bed.

2. Sleeping quarters in the car of an aerial vessel comprising tiers of beds at one side of a main passage and on either side of a lateral passage in communication with the main passage, the beds being arranged parallel with the lateral passage, means for providing separate dressing rooms for each of the beds comprising for one of the beds in a tier a chamber-like compartment at that end of the tier adjacent the main passage, and for the other bed in said tier a chamber-like compartment arranged in the lateral passage and opening onto said other bed, said last-mentioned compartment being arranged at the entrance to the lateral passage whereby a space is left at the foot of the lateral passage, said space constituting a dressing room for one of the beds in the other tier.

3. The combination specified in claim 2, the chamber-like compartment in the lateral passage being flexible curtains.

4. The combination specified in claim 1, the chamber-like partitioning means at the front ends of the beds being flexible curtains.

In witness whereof, I have hereunto subscribed my name in presence of two witnesses.

FRITZ GENTZCKE.
